DESIGN FOR COMBINED SKI PANTS AND SPATS

Benjamin Fischer, New York, N. Y.

Application May 13, 1936, Serial No. 62,620

Term of patent 3½ years

To all whom it may concern:

Be it known that I, Benjamin Fischer, a citizen of the United States of America, residing in Manhattan, county of New York, and State of New York, have invented a new, original, and ornamental Design for Combined Ski Pants and Spats, of which the following is a specification, reference being had to the accompanying drawing, forming part thereof, wherein,

Figure 1 is a front view of combined ski pants and spats showing my new design.

Figure 2 is a rear view of the combined ski pants and spats shown in Figure 1.

Figure 3 is an enlarged side view of the spat portion.

The characteristic feature of my design resides in the combination on a pair of bloused ski trousers of permanently attached spats as shown.

I claim:

The ornamental design for combined ski pants and spats, substantially as shown, and described.

BENJAMIN FISCHER.
